THRESHER CONSTRUCTION

Melville J. Mitchell, Moline, Ill., assignor to International Harvester Company, a corporation of New Jersey

Application September 29, 1939, Serial No. 297,137

12 Claims. (Cl. 130—27)

This invention relates to a thresher construction. More specifically it relates to a housing for parts of the thresher mechanism.

It is the usual practice to support the parts of a thresher mechanism upon angle members forming a framework and to cover the angle members with sheets which form a shell. The present tendency toward streamlining and the wide spread use of welding demand and make possible a more unitary construction. The present invention contemplates a construction by which various stiffening members are secured to a thresher shell so that the shell itself is strong enough to support parts of the thresher body.

An object of the present invention is to provide an improved thresher construction.

Another object is the provision of a construction in which various stiffener members and a shell are joined to form a unitary structure for the support of thresher parts.

According to the present invention, an inverted U-shaped shell is provided for the support of parts of the thresher mechanism. The shell by itself is of insufficient rigidity to support the thresher mechanism, and consequently various other parts are welded or otherwise secured to the shell to give the shell the requisite structural strength and stiffness.

In the drawings:

Figure 1 is a side view of the improved thresher body;

Figure 2 is a plan view of the same;

Figure 3 is a section taken along the line 3—3 of Figure 2;

Figure 4 is a section taken along the line 4—4 of Figure 1;

Figure 5 is a section taken along the line 5—5 of Figure 4;

Figure 6 is a section taken along the line 6—6 of Figure 2;

Figure 7 is a section taken along the line 7—7 of Figure 1;

Figure 8 is a section taken along the line 8—8 of Figure 1; and,

Figure 9 is a section taken along the line 9—9 of Figure 8.

The thresher construction of the present invention, as shown in Figures 1 and 2, comprises an inverted U-shaped shell 15 adapted to house a thresher mechanism, not shown, an axle 16 supported on wheels 17 and 18, and a draw frame 19. The draw frame comprises three longitudinally extending members 20, 21 and 22 braced by cross members 23. The members 20, 21, and 22 extend in diverging relationship from gen-

erally a common point. The member 20 is connected at one end of the axle 16 outside the wheel 18. The member 21 is connected adjacent the midpoint of the axle. The member 22 extends through an opening in the top 24 of the shell 15 and is secured by bolts 25 to the top 24 and to a stiffening member 26 secured inside the top of the shell and extending as an extension of the member 22.

The U-shaped shell 15 comprises the top 24 and a pair of sides 27 and 28 welded thereto. The shell 15 is stiffened by a plurality of channel members 29, 30, 31 and 32 secured as by welding to the outside of the shell. As illustrated in Figure 7, the channel 29 is semi-circular in shape and has flanges 33 at its edges welded to the side 28 of the shell 15. The channels 30, 31 and 32 are of similar conformation. The channels 29 and 30 extend only along the sides 27 and 28. The channels 31 and 32 extend along the sides 27 and 28 and over the top 24. Figures 8 and 9 show a channel member 34 welded to the inside of the top 24 as a stiffening means. The channel member 34 comprises a base 35, side 36 and side 37, which is welded to the top 24. There is a plurality of these channel members secured in parallel spaced relation to the inside of the top 24. The shell 15 is also strengthened by means of a grain elevator housing 38 secured to the side 28 and a tailings elevator housing 39 secured to the side 27. As illustrated in Figures 4 and 5, the housing 38 is secured to one side of a channel member 40, the other side of which is secured to the side 28 of the shell 15. The tailings elevator housing 39 is secured in similar fashion to the side 27 by means of a channel member 40.

The shell 15 also includes a downwardly opening hood 41 at the rear thereof which comprises a curved top piece 42 and sides 43 and 44, the parts being secured together as by welding. This hood has an outwardly extending bead 45 along its lower edge.

As shown in Figure 3, the axle 16 passes through the sides 27 and 28 of the shell 15. The axle is composed of tubular sections 46 and 47 sleeved over and secured to one another by means of a tubular member 48 to which the parts are pinned as at 49. Pins 50 secure the section 46 of the axle to the tubular member 48 and to a tubular sleeve 51 secured in the side 27 by means of brace members 52 and 53. Angle members 54 and 55 extend respectively along the lower edges of the sides 27 and 28 so as to stiffen the shell. Plates 56 and 57 extend below the edges of the

sides 27 and 28. The wheels 17 and 18 are journaled respectively on the journal members 53 and 59 at the ends of the axle, and there are tie members 60, 61 and 62 extending from said members to the shell 15. Upwardly extending members 63 and 64 rest on the top 24 of the shell 15 and on the channels 31 and 32 and are adapted to serve as a support for driving motor, not shown.

It will be appreciated from the above description that a new and novel thresher body construction has been provided. The shell 15, which by itself is of insufficient rigidity to support parts of the thresher mechanism, is reenforced by various members so that it has the requisite stiffness. Consequently, parts of the thresher mechanism may be supported directly in the walls 27 and 28 of the shell. Openings 65 and 66 in the side 28 are adapted to receive drive shafts of the thresher mechanism, not shown. No thresher mechanism has been illustrated since it forms no part of the present invention.

It is the intention to limit the invention only within the scope of the appended claims.

What is claimed is:

1. A thresher construction comprising a wheel-supported axle, a draw frame including three members extending in diverging relationship from generally a common point, two members being secured respectively at the end and at a mid-point of the axle and the third member extending in spaced relation to and above a mid-point of the axle, and an inverted U-shaped thresher shell secured to and over the axle alongside the draw frame in transverse relationship with the axle and having its top secured to the third member of the draw frame.

2. A thresher construction comprising a wheel-supported axle, a draw frame including three members extending in diverging relationship from generally a common point, two members being respectively secured at the end and at a mid-point of the axle and the third member extending in spaced relation to and above a mid-point of the axle, and an inverted U-shaped thresher shell secured to and over the axle alongside the draw frame in transverse relationship with the axle and having its top secured to the third member of the draw frame and having spaced stiffening members secured to its sides.

3. A thresher construction comprising a wheel-supported axle, a draw frame including three members extending in diverging relationship from generally a common point, two members being respectively secured at the end and at a mid-point of the axle and the third member extending in spaced relation to and above a mid-point of the axle, an inverted U-shaped thresher shell secured to and over the axle alongside the draw frame in transverse relationship with the axle and having its top secured to the third member of the draw frame, and elevators secured to the sides of the shell so as to stiffen the same.

4. A thresher construction comprising a wheel-supported axle, a draw frame including three members extending in diverging relationship from generally a common point, two members being respectively secured at the end and at a mid-point of the axle and the third member extending in spaced relation to and above a mid-point of the axle, an inverted U-shaped thresher shell secured to and over the axle alongside the draw frame in transverse relationship with the axle and having its top secured to the third member of the draw frame, and stiffening means for the

shell, comprising a channel member having one side secured to a side of the shell and an elevator housing secured to the other side of said member.

5. A thresher construction comprising an inverted U-shaped shell and stiffening means therefor comprising a first channel member having one side secured to one side of the shell, a grain elevator housing secured to the other side of said member, a second channel member having one side secured to the other side of the shell, and a tailings elevator housing secured to the other side of the second channel member.

6. A thresher construction comprising a wheel-supported axle, a draw frame including three members extending in diverging relationship from generally a common point, two members being secured at the end and at a mid-point of the axle, and a third member extending in spaced relation to and above a mid-point of the axle, and an inverted U-shaped thresher shell secured to and over the axle alongside the draw frame in transverse relationship with the axle and having the under side of its top secured to the third member of the draw frame.

7. A thresher construction comprising a wheel-supported axle, a draw frame including three members extending in diverging relationship from generally a common point, two members being secured at the end and at a mid-point of the axle, and a third member extending in spaced relation to and above a mid-point of the axle, and an inverted U-shaped thresher shell secured to and over the axle alongside the draw frame in transverse relationship with the axle and having a stiffening member secured to the under side of the top of the shell and to the third member of the draw frame, and extending generally in alignment with and as an extension of the said third member.

8. A thresher construction comprising a wheel-supported axle, a draw frame including three members extending in diverging relationship from generally a common point, two members being secured at the end and at a mid-point of the axle and the third member extending in spaced relation to and above a mid-point of the axle, and an inverted U-shaped thresher shell secured to and over the axle alongside the draw frame in transverse relationship with the axle and having its top secured to the third member of the draw frame, said shell having a downwardly opening hood at one end thereof provided with an outwardly beaded edge.

9. A thresher construction comprising a wheel-supported axle, a draw frame including three members extending in diverging relationship from generally a common point, two members being secured at the end and at a mid-point of the axle and the third member extending in spaced relation to and above a mid-point of the axle, an inverted U-shaped thresher shell secured to and over the axle alongside the draw frame in transverse relationship with the axle and having its top secured to the third member of the draw frame, and elevators secured to the sides of the shell so as to stiffen the same, said shell having a downwardly opening hood at one end thereof provided with an outwardly beaded edge.

10. A thresher construction comprising a wheel-supported axle, a draw frame including three members extending in diverging relationship from generally a common point, two members being secured at the end and at a mid-point of the axle and the third member extending in

spaced relation to and above a mid-point of the axle, an inverted U-shaped thresher shell secured to and over the axle alongside the draw frame in transverse relationship with the axle and having its top secured to the third member of the draw frame, said shell having a downwardly opening hood at one end thereof provided with an outwardly beaded edge, and stiffening means for the shell, comprising a channel member having one side secured to a side of the shell and an elevator housing secured to the other side of said channel member.

11. A thresher construction comprising a wheel-supported axle, a draw frame including three members extending in diverging relation from a common point, two members being secured respectively at the end and at a mid-point of the axle, and the third member extending in

spaced relation to and above a mid-point of the axle, and a thresher shell secured to and over the axle alongside the draw frame in transverse relationship with the axle and having its top secured to the third member of the draw frame.

12. A thresher construction comprising a wheel-supported axle, a draw frame including three members extending in diverging relation from a common point, two members being secured respectively at the end and at a mid-point of the axle, and the third member extending in spaced relation to and above a mid-point of the axle, and a thresher shell secured to and over the axle alongside the draw frame in transverse relationship with the axle and having the under-side of its top secured to the third member of the draw frame.
